9 Claims. (Cl. 12—57.2)

1

The present invention relates to the manufacture of turned footwear, such as slippers (babouches), gymnasium shoes or the like, and more particularly to an apparatus for turning the toe part of turned footwear.

The operation of turning the toe part of footwear of the kind specified is normally carried out on turning machines which usually comprise two forms, the work receiving form and the counter-form, the toe portion of the shoe under treatment being clamped between the two forms; in this condition the shoe is pulled from the work receiving form in a direction towards the counter-form, this operation being effected by the operator for the most part manually. In order to make the operation less tiresome, it has been proposed to provide the work receiving form with a pair of distending fingers which by their distending motion assist the operator in his work during the turning of the shoe. However, the distending fingers are arranged in such a way that they are of assistance to the operator in the first stage only of his work, the turning of the shank portion of the shoe, when due to the relatively large distance of this portion from the shoe part clamped between the forms, no particular effort is required, while the said fingers are not of any use during the turning of the toe part, although in this phase of the turning operation their aid would be the most desirable.

The apparatus in accordance with the present invention permits to eliminate the disadvantage of the prior arrangement referred to and to carry out the turning of footwear almost without manual work, since the work to be effected by hands consists at most in holding the footwear in position, but not at all in turning the same.

The essence of the invention consists in an arrangement in which the work receiving form is associated with a belt of flexible material which is adapted to be controlled by means of a roller system in such a way as to be extended and then bent over at the rear of the toe part of a shoe clamped between the end of the work receiving form and that of the counter-form, whereby the footwear is turned and pulled over from the work receiving form onto the counter-form. The belt controlling rollers are capable of performing translatory motion in the axial direction of the work receiving form, the yielding nature of the tensioning and extending effect on the belt being obtained by providing for a resilient mounting of the said rollers.

Further advantages and features of the present invention will appear from the following de-

2

scription when read in conjunction with the accompanying drawings, in which

Fig. 1 shows the general lay-out of the machine in inoperative position;

5 Figs. 2 to 4 show diagrammatically the various phases of the working process; and

Fig. 5 shows a detail of the arrangement of the counter-form.

The apparatus is provided with a work receiving form 1 which is mounted slidably in a sleeve 2 carried by the machine frame 3. The form 1 may be shifted by means of a screw 4 and a nut 5. The sleeve 2 has fastened thereon by means of screws 6 the two ends of a belt 7 which is passed through an opening 8 provided in the form 1. The belt 7 may be made of leather, rubber, cord or a similar flexible and strong material. Both end portions of the belt 7 pass between tensioning rollers 9 and 10, of which the 10 rollers 9 are mounted on pivots 11 carried by a double armed fork 12 and the rollers 10 are mounted at the ends of small arms 13 which are rotatable about the pivots 11 and are connected together by means of a spring 14. The double- 15 armed fork 12 is mounted in a forked bracket 15, the work receiving form 1 passing through the forked part of said bracket. The bracket is 20 mounted on a rod 16 which has its one side provided with rack teeth 17. The other end of the rod 16 is mounted in a sleeve provided in the machine frame 3. The bracket 15 is guided by means of an auxiliary guide rod 18 which is mounted in a sleeve also provided in the machine frame 3. The bracket 15 with the tensioning 25 rollers 9 and 10 is driven in the direction of the arrow 11 by means of a gear wheel 19 meshing with the rack teeth 17 on the rod 16. The bracket 15 is caused to move in the opposite direction by means of a counter-weight (not 30 shown) which is hung from a chain 20 passing around a sprocket 21 and connected to a pin 22 on the bracket 15.

At a location opposite to that of the work receiving form 1 there is provided a counter-form 23 fastened in a holder 24, as shown in Figs. 1 and 5. The holder 24 is mounted for rocking movement around a pivot 25 fastened in a bracket 26. The latter is mounted rotatably on a link 27 and is moved up and down by the said link. A spring 28 tends to cause the holder 24 to rock about the pivot 25 in clockwise direction, this movement being limited by a stop screw 29. The pivot 25 carries also a guide-roller 30 which during the vertical movement of the link 27 rolls 35 on a lateral runway 31 thereby causing the

bracket 26 to turn about the link 27. The roller 30 is pressed against the runway 31 by means of a spring 32 shown in Fig. 5. The link 27 is guided in a sleeve 33 on the machine frame 3 and receives vertical motion from a cam 34 by means of a lever 35 rotatable about a pivot 36. The cam is arranged on the same shaft 37 as the gear wheel 19. The lever 35 is urged constantly downwards by means of a spring 38. The shaft 37 receives one-revolution drive from a motor (not shown) by means of a one-revolution clutch of any desired type, the said clutch interrupting at the same time the connection between the gear wheel 19 and the shaft 37. The clutch itself is controlled by a foot lever through the intermediary of a connecting rod 39.

The apparatus as thus far described operates in the following manner:

The fundamental position of the apparatus is shown in Fig. 1. In this position the link 27 is in its lowest position and the counter-form 23 has been deflected out of parallelism with respect to the axis of the work receiving form 1 by the lateral runway 31 acting on the roller 30 of the bracket 26. The object of such a deflection is to facilitate the access to the work receiving form. In this position the operator introduces the work receiving form into a shoe until the point of the form abuts against the toe of the shoe. During this operation the belt 7 passes between the upper and the sole of the shoe. By depressing the foot lever (not shown) the connecting rod 39 will cause the one-revolution clutch to drive the shaft 37, the gear wheel 19 being connected at the same time with the shaft 37 by means of the said clutch. The cam 34 will cause the lever 35 to rock in upward direction whereby the link 27 will bring the counter-form 23 to the position shown in Fig. 2 in which the counter-form will force the toe of the shoe against the point of the work receiving form. The counter-form remains in this position during the entire turning operation. During the upward movement of the bracket 26 the lateral runway 31 will permit angular movement of the counter-form 23 back into the direction of the axis of the work receiving form 1 under the action of the spring 32. As soon as the counter-form has clamped the toe of the footwear against the point of the work receiving form 1, as shown in Fig. 2, the gear wheel 19 will engage with the rack teeth 17 on the rod 16 and will carry along the said rod with the forked bracket 15 in the direction of the arrow S1. This results in the belt 7 being tensioned by the rollers 9, 10, and the upper and sole of the footwear being distended. Concurrently the turning of the shoe takes place, more particularly at the stage when the bracket 15 has assumed such a position that the rollers 9 are located in advance of the point of the work receiving form, as shown in Fig. 3. At this stage also the spring 14 of the arms 13 carrying the rollers is tensioned under the effect of the tension of the belt 7, so that finally the apparatus will assume the position shown in Fig. 4 in which the shoe is turned already and is carried by the counter-form 23. At this moment the clutch will interrupt the connection between the gear wheel 19 and the shaft 37, so that the bracket 15 with the rod 16 will return to its original position under the action of the counter-weight connected to the chain 20. The cam 34 ceases to act on the lever 35 and the latter swings downwards under the action of the spring 38, the bracket 26 with the counter-form 23 being returned to their lower

position, shown in Fig. 1, by the effect of the link 27. Under the action of the lateral runway the counter-form 23 with the holder 24 will be deflected out of the direction of the axis of the work receiving form and the operator can remove without difficulty the turned shoe from the counter form, whereby the cycle of operations is terminated.

The apparatus and method in accordance with the present invention are suitable for use more particularly in connection with the turning of footwear with stiff sole, such as slippers (babouches) which operation has been very tiresome with the devices as hitherto used.

What I claim is:

1. In an apparatus for the manufacture of turned footwear, a work receiving form, a belt of flexible material associated therewith, a counter-form co-operating with the work receiving form, and means for controlling the belt in such a way as to extend the same and then bend it over the toe portion of a shoe clamped between the end of the work receiving form and that of the counter-form, whereby the shoe is turned and pulled over from the work receiving form into the counter-form.

2. In an apparatus for the manufacture of turned footwear, a work receiving form, a belt of flexible material associated therewith, a counter-form co-operating with the work receiving form, and means movable in the direction of the axis of the work receiving form for controlling the belt in such a way as to extend the same and then bend it over the toe portion of a shoe clamped between the end of the work receiving form and that of the counter-form, whereby the shoe is turned and pulled over from the work receiving form onto the counter-form.

3. In an apparatus for the manufacture of turned footwear, a work receiving form, a belt of flexible material associated therewith, a counter-form co-operating with the work receiving form, means for controlling the belt in such a way as to extend the same and then bend it over the toe portion of a shoe clamped between the end of the work receiving form and that of the counter form, and means controlled by the machine drive for imparting axial movement to the belt controlling means in the direction of the axis of the work receiving form.

4. In an apparatus for the manufacture of turned footwear, a work receiving form, a belt of flexible material associated therewith, a counter form co-operating with the work receiving form, means for controlling the belt in such a way as to extend the same and then bend it over the toe portion of a shoe clamped between the end of the work receiving form and that of the counter-form, means controlled by the machine drive for imparting axial movement to the belt controlling means in the direction of the axis of the work receiving form, and means for imparting vertical movement to the counter-form.

5. In an apparatus for the manufacture of turned footwear, a work receiving form, a belt of flexible material associated therewith, a counter-form co-operating with the work receiving form, means for controlling the belt in such a way as to extend the same and then bend it over the toe portion of a shoe clamped between the end of the work receiving form and that of the counter-form, means controlled by the machine drive for imparting axial movement to the belt controlling means in the direction of the axis of the work receiving form, means for imparting

vertical movement to the counter-form, and means for controlling the rocking movement of the counter-form.

6. In an apparatus for the manufacture of turned footwear, a work receiving form, a belt of flexible material associated therewith, a counter-form co-operating with the work receiving form, a roller system for controlling the belt in such a way as to extend the same and then bend it over the toe portion of a shoe clamped between the end of the work receiving form and that of the counter-form, a bracket controlled by the machine drive for imparting axial movement to the belt controlling rollers in the direction of the axis of the work receiving form, a link operated by the machine drive for imparting vertical movement to the counter form and a lateral runway co-operating with a spring urged roller to control the rocking movement of the counter-form.

7. In an apparatus for the manufacture of turned footwear, a work receiving form, a roller system comprising two pairs of rollers for controlling the belt in such a way as to extend the same and then bend it over the toe portion of a shoe clamped between the end of the work receiving form and that of the counter-form, a bracket controlled by the machine drive for imparting axial movement to the belt controlling rollers in the direction of the axis of the work receiving form, a link operated by the machine drive for imparting vertical movement to the counter-form and a lateral runway co-operating with a spring urged roller to control the rocking movement of the counter form.

8. In an apparatus for the manufacture of turned footwear, a work receiving form, a belt of

flexible material associated therewith, a counter-form co-operating with the work receiving form, a belt controlling roller system comprising two pairs of rollers, one roller of each pair being mounted rotatably on a pivot carrying a rocking arm on which the second roller of the pair of rollers is rotatably mounted, a bracket controlled by the machine drive for imparting axial movement to the belt controlling rollers in the direction of the axis of the work receiving form, a link operated by the machine drive for imparting vertical movement to the counter-form, and a lateral runway co-operating with a spring urged roller to control the rocking movement of the counter-form.

9. In an apparatus for the manufacture of turned footwear, a work receiving form, a belt of flexible material associated therewith, a counter-form co-operating with the work receiving form, a belt controlling roller system comprising two pairs of rollers, one roller of each pair being mounted rotatably on a pivot carrying a rocking arm on which the second roller of the pair of rollers is rotatably mounted, the two roller carrying arms being resiliently connected to each other, a bracket controlled by the machine drive for imparting axial movement to the belt controlling rollers in the direction of the axis of the work receiving form, a link operated by the machine drive for imparting vertical movement to the counter-form, and a lateral runway co-operating with a spring urged roller to control the rocking movement of the counter-form.
